UNITED STATES PATENT OFFICE

ALBERT A. GORDON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

COLOR-SLIDE CONTROL FOR MULTICOLOR MAGAZINES

Application filed June 8, 1928. Serial No. 283,975.

This invention relates to means for controlling movements of the color slide of an automatic multicolor weft replenishing mechanism and it is the general object of the 5 invention to simplify the controls for the color slide by eliminating moving parts heretofore considered necessary in this type of motion.

The ordinary multicolor weft replenishing mechanism embraces in its construction a longitudinally and angularly movable color slide which moves under control of the box motion or pattern mechanism to assume a plurality of positions dependent upon the 10 number of shuttle boxes and movable angularly in opposite directions to effect releasing of bobbins from the magazine. As usually constructed there is a bell crank lever having a pin and grooved collar connection with 15 the color slide, the lever being connected to some portion of the box motion or pattern mechanism by intermediate connections and being supported by a separate casting which is bolted to the main frame of the magazine. 20 It is an important object of my present invention to extend the color slide and associate therewith a yielding element which is stressed in a direction substantially parallel to the axis of the color slide and acts to move the 25 color slide in one direction.

It is a further object of my present invention to form a sliding rod which serves as part of the color slide with an extension around which is mounted a tension spring 30 one end of which is held by fixed structure and the other end of which is operatively related to the rear end of the rod, said spring operating to move the color slide forwardly.

With these and other objects in view which 40 will appear as the description proceeds, my invention resides in the combination and arrangement of parts hereinafter described and set forth in the claims.

In the accompanying drawings wherein a 45 convenient embodiment of my invention is set forth,

Fig. 1 is a side elevation of a portion of a color magazine having my improved form of color slide applied thereto, the same being 50 viewed from the interior of the loom,

Fig. 2 is a detailed horizontal section on line 2—2 of Fig. 1, and

Fig. 3 is a diagrammatic view showing the connections for the color slide.

Referring particularly to Fig. 1, the magazine stand 10 is provided with a plurality of vertical slides 11, 12, 13 and 14, respectively, each of which is provided with an upper lug 15 and a lower lug 16. By means of pins 17 formed in rocking members 18 and slots 19 formed in the lower end of the vertical slides the latter are effective to control the release of bobbins B from the several stacks of the magazine. As shown in Fig. 2 the frame of the magazine is provided with a plurality of flanges 20 which define guideways for the stacks of bobbins.

The color slide comprises a rod 21 which slides in a horizontal direction through guide bearings 22 formed as parts of the magazine frame and there is secured to said rod a casting 23 from which project a pair of fingers 24 one of which is shown in Fig. 2. Said fingers cooperate with the lugs 15 and 16 to raise and lower the vertical slides.

The color slide is provided with a fin or web 25 which slides through a rocking member 26 positioned vertically by a rod 27. The rod 27 is given an upward motion every alternate beat of the loom when the shuttle is on the drop box end of the loom and is given a downward movement whenever the weft detector, not shown, indicates substantial weft exhaustion. By these two movements of the rod 27 the rod 21 is rocked in its bearings.

The matter thus far described is substantially the same as that shown in Ryon Patent No. 1,030,748 to which reference may be had for a further and more complete description of the structure and operation in the device as shown herein.

My present invention relates particularly to the means for moving the color slide to the right as viewed in Fig. 1 and in carrying my invention into effect I extend the rod 21 rearwardly as at 40 and dispose therearound a tension spring 41. The right hand end of said spring is bent as at 42 to extend over the rear bearing 22 and is hooked as at 43 around the rod 21 on the right hand or forward side of

said bearing 42. In this way the right hand end of the spring as shown in Fig. 1 is limited as to movement to the left.

The rear end of the extension 40 is perforated as at 44 and has the rear end of the spring 41 extended therethrough as at 45. If desired a ring 46 may also extend through the perforation 41 and be attached to a chain 47 which as shown in Fig. 3 may extend over an idler sheave 48. Said chain 47 is connected to a lever 49 located at the opposite end of the loom and positioned by mechanism operated by the box motion or if desired by any mechanism controlled by the pattern mechanism not shown. It is sufficient for my present purposes to state that the chain 47 will be moved to give the rod 21 as many different longitudinal positions as there are vertical slides on the magazine.

In operation, as the boxes shift to bring the several shuttles into action one at a time the chain 47 will move, either exerting a pull on the rod 21 against the action of spring 41 or permitting said spring 41 to move the rod 21 to the right, depending upon the sequence in which the shuttles become active. The spring 41 will act at all times to keep the chain 47 taut and will keep the fingers 24 accurately positioned with respect to the lugs 15 and 16.

From the foregoing it will be seen that I have provided a very simple means for yieldingly controlling the position of the color slide rod 21, involving merely an extension of said rod to have located therearound a spring tending to move the rod forwardly. This eliminates the use of the bell crank lever customarily employed and set forth in the aforesaid patent to Ryon. It will further be seen that one of the bearings through which the rod 21 extends serves as an anchor for the forward end of the spring.

Having thus described my invention it will be seen that changes and modifications may be made therein by those skilled in the art without departing from the spirit and scope of the invention and I do not wish to be limited to the details herein disclosed, but what I claim is:

1. In a multicolor weft replenishing mechanism, an angularly and longitudinally movable color slide, a rod forming part of said color slide, an extension on said rod extended rearwardly and having a perforation therein, a bearing through which the rod passes, and a tension spring surrounding the extension of the rod and having the rear end thereof passing through the perforation and having the forward end attached to the bearing, said spring tending normally to move the rod yieldingly in one direction.

2. In a multicolor weft replenishing mechanism, an angularly and longitudinally movable color slide, a rod forming part of said color slide, a bearing for the rod, the rod be-

ing extended rearwardly behind the bearing, and a tension spring surrounding the extended part of the rod and having the rear end operatively connected to the rod and tending to move the latter forwardly, the forward end of the spring being passed around the bearing and also that portion of the rod lying in front of the bearing to anchor said forward end to the spring.

3. In a multicolor weft replenishing mechanism, an angularly and longitudinally movable color slide, a rod forming part of said color slide, said rod having a perforation therein, a bearing through which the rod passes, and a spring having a part to enter the perforation and having another part attached to the bearing, said spring tending normally to move the rod yieldingly in one direction.

In testimony whereof I have hereunto affixed my signature.

ALBERT A. GORDON.
